Attorney

UNITED STATES PATENT OFFICE

EUGENE ROBERTS, OF HASTINGS, NEW YORK

LOADING GAUGE FOR CENTRIFUGAL BASKETS

Application filed July 19, 1930. Serial No. 469,186.

This invention relates to centrifugals of the type used in sugar refineries and the like for centrifugally extracting juices or liquid from solid grains of material with which the liquid is mixed and is intended to provide a means for accurately gauging the thickness of the sugar or other material that is walled-up on the inside of the centrifugal basket during the operation of the machine. Heretofore, the individual operator has been obliged to depend on his own judgment as to the thickness of the sugar wall to be built up inside the basket for treatment, which is determined primarily by the amount of wet sugar or raw material that is admitted into the centrifugal basket through the supply or delivery spout. In practice, the thickness of the sugar wall varies greatly under this method of dealing with the loading of the machine, with the result that too thin a wall reduces the capacity output of the machine, while too thick a wall makes it difficult with some grades of sugar to properly extract the liquid which must find its way through the wall to the perforated surrounding wall of the basket.

The present invention provides a means for obviating these troubles by furnishing an automatic gauge that will plainly indicate to the attendant the fact that a predetermined thickness of wall has been reached. Furthermore, the device is capable of being used merely as an indicator to inform the operator when the supply of material should be cut off, or it may be used to cut off the supply of material automatically in various ways.

To this end the invention comprises a contact member or gauge movably supported in position to project inside the centrifugal basket toward the peripheral wall thereof, its position being determined by predetermined adjustments according to the thickness of the wall of material that is to be built up in any particular case. This gauging member, when the wall has reached the predetermined thickness, is then pushed outwardly by contact with the inside face of the sugar wall, thereby giving visible indication that the supply should be cut off. This and

other features characterizing the invention will be particularly explained in the following specification and will be defined in the claims hereto annexed.

In the accompanying drawing

Fig. 1 represents in front elevation the parts of a centrifugal machine necessary to an understanding of this improvement with which are associated the various parts for gauging the thickness of the sugar wall and cutting off the supply of sugar.

Fig. 2 is an enlarged detail view showing in plan a portion of the top of the curb or casing surrounding the centrifugal basket on which is mounted the gauging device.

Fig. 3 is a vertical section through the basket wall and curb showing in elevation the gauging device.

Fig. 4 is a front elevation shown in section showing a modified form of actuating device for automatically shutting off the flow of material to the basket.

Fig. 5 is a detail view showing in side elevation the electric terminal and contact piece on the outer end of the pointer.

In the accompanying drawing is shown a well known type of sugar centrifugal basket 3 surmounted by the usual inclined top ring or plate 4 and surrounded by the usual closed curb or casing 1 having an inwardly projecting top ring 2 overhanging the top of the centrifugal basket. The centrifugal basket is suspended from any well known type of overhead bearing not here shown by means of a central suspension shaft 5.

The sugar delivery spout 7 leads down from the usual overhead mixer and its open delivery nozzle is closed by a circular gate or plate 8 attached to a hand lever 9, fulcrumed at 10, and usually carrying on its rear end a counterbalance weight 11. These delivery spouts and closing gates are well known in the art and may be of any suitable construction with the usual accessories not necessary to be shown in this case.

Upon the top ring 2 of the basket surrounding casing is mounted a bracket 15 of any suitable form, but which in this case is in the form approximately of a T, whose radial arm is bolted to the top ring so as to

overhang the inner edge of the top ring. At its inner end the bracket 15 is provided with a bearing boss 15^a, in which is mounted a rotatable spindle 16 to whose lower end is 5 secured a spoon-like paddle or gauge member 17^a.

A torsion spring 19 tends to swing the spindle 16 in a counterclockwise direction. On the upper end of the spindle 16 is secured 10 an indicator arm or finger 18, which projects outwardly beyond the cross member 15^b of the supporting bracket, and this cross member is provided with a series of spaced holes or sockets 15^c substantially parallel with the 15 periphery of the curb. A removable stop pin 29 is adapted to be inserted in any one of these socket openings according to the thickness of sugar wall which it is desired to build up inside the basket. This stop pin in 20 its various positions of adjustment serves to limit the inward movement or travel of the gauge member 17^a to any desired distance away from the peripheral wall of the basket 3 and therefore determines the gauging position at which the building-up wall of sugar 25 comes in contact with the gauge member 17^a, which contact serves to push the gauge member inwardly toward the center of the basket, thereby causing the indicator arm or pointer 30 18 to swing away from the stop pin 29. If the pin in the middle position, as shown, faces the position of the gauge member 17^a at four inches from the peripheral wall of the basket, then any increase of thickness of the sugar 35 wall beyond four inches moves the pointer away from the stop pin and by that fact indicates that the four inch thickness has been reached.

As this indicator or pointer is in plain 40 sight of the operator, he is instantly apprised that the wall has built up to the four inch thickness and has merely to close the gate 8, which admits the material into the basket. thus cutting off the supply.

The centrifugal foreman can set these pins 45 according to his expert judgment and the operators no longer depend upon their individual judgment but have a plain, reliable indication when the time comes to cut off the supply.

The same apparatus may be used to automatically cut off the supply of sugar to the basket at a predetermined point in various ways.

In Fig. 1 is illustrated an arrangement by 55 which the gauge and its connected indicating pointer may be employed to energize an electrically controlled gate-actuating motor in the form of a solenoid 25 mounted above the centrifugal, whose plunger 25^a is provided with a link connection 26 with lever 27 fulcrumed at 27^a and carrying at its free end a pivotal link 28, terminating at its lower 60 end in a hook 28^a positioned below the short weighted arm of the lever 9.

An electric conductor α is attached to the free end of the pointer 18 and carries an insulated contact plate 18^a on the side opposite the stop pin 29 arranged in position to form a contact with a terminal pin 20, which is connected with the solenoid by the other wire γ of the electric circuit. Obviously, so long as the torsion spring 19 keeps the pointer 18 in contact with the stop pin 29, the circuit $\alpha\gamma$ is open, but when the gauge is moved inward a short distance against the tension of the spring by contact of the sugar wall the contact plate 18^a comes in contact with the terminal pin 20 to close the circuit. To prevent short-circuiting or grounding the terminal pin 20 is covered with a ring of insulating material 20^a, which fits into the row of sockets 15^c.

Instead of using an electric current to operate the actuating arm 27 that closes the delivery spout, I may use a smaller electric actuator 30, which acts to control the application of power to indirectly cause the closing of the gate 8.

In Fig. 4 I have illustrated a compressed air cylinder 31, whose reciprocating piston 32 is connected with the gate-actuating link 27, the compressed air being admitted through a valve chamber 33 by means of a rocking valve 34 which admits compressed air from the air line pipe 35 in one position and which vents the compressed air cylinder in the other position, the actuating arm attached to the end of said valve being connected by means of links 36, 37 with a small magnet or solenoid 30.

Hence, it will be seen that the motor or actuator, which moves the gate arm 9, may be actuated directly by means of the current closed by the pointer 18, or said gate arm may be actuated by a separate motor device whose action is controlled by the closing of the circuit or by the indicator or pointer.

It will be seen that the socket piece, in which the stop pin is adjustably mounted, constitutes in effect an indicating dial in association with the pointer to indicate different distances of the outside face of the contact arm from the basket wall, so that when the contact arm begins to move inward the thickness of the sugar wall is plainly indicated.

What I claim is:

1. Means for controlling the loading of a centrifugal basket, embracing a contact member supported inside the basket and adjustable to any predetermined distance from the wall of the basket, a cut-off valve for cutting off the supply of material to the basket, means for closing said cut-off valve, said means being set in action by the closing of an electric circuit through a terminal that is adjustable to various positions, and a circuit closer actuated by the movement of the con-

tact member into contact relation with said adjustable terminal.

2. In a loading control device for a centrifugal basket, the combination of a contact arm mounted to permit inward and outward movement of the contact arm, means normally acting to move said contact member outwardly toward the basket wall, an indicating pointer connected with the contact arm to move therewith, said pointer being mounted above the basket and its casing and movable against an adjustable stop member which limits the outward movement of the contact arm to predetermined distances from the basket wall.

3. The combination with a centrifugal comprising a centrifugal basket and its casing, a vertical rock spindle mounted in a support projecting inwardly from the top of the casing, a contact arm secured to the lower end of said spindle to permit movement inside the basket toward and from the basket wall, a spring connected with said spindle to normally press the contact arm outward, an outwardly projecting pointer secured to the upper end of said spindle and movable over a series of sockets, and a stop pin insertable into any predetermined socket to limit the outward movement of the contact arm by engagement of the pointer with said stop pin, the contact arm being movable inwardly under pressure of the built-up wall of material and thereby giving indication of the thickness of the built-up wall through the movement of the pointer away from the stop pin.

4. A loading gauge for a centrifugal basket embracing, a contact member mounted to have movement toward any away from the central basket shaft and disposed in position to be engaged by the inwardly building wall of material and to be moved thereby toward said central shaft in correlation with the thickness of said inwardly built material and an indicating pointer operably connected with and moved by said contact member over an associated dial to indicate the thickness of the walled-up material inside of the basket.

In witness whereof, I have subscribed the above specification.

EUGENE ROBERTS.
